SEWING MACHINE OR SIMILAR ARTICLE

Susumu Hanyu, Tokyo, Japan, assignor to Janome
Sewing Machine Co., Limited, Tokyo, Japan

Filed June 11, 1962, Ser. No. 70,490

Term of patent 14 years

(Cl. D70—2)

FIG. 1

FIG. 1 is a top plan view of a sewing machine showing my new design;

FIG. 2 is a front elevational view thereof; and

FIG. 3 is a front quarter perspective view.

The dominant features of the design reside in the portions shown in full lines and the particular arrangement, as shown.

I claim:

The ornamental design for a sewing machine or similar article, as shown and described.
